CLAIM

We claim the ornamental design for a vacuum cleaner with wet floorcloth, as shown and described.

DESCRIPTION

FIG. 1 is a perspective view of a vacuum cleaner with wet floorcloth showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a front elevation view showing when a LED light in the front of main body thereof is on as being expressed by a stipple pattern.
